US00D741332S

(12) **United States Design Patent**
Thompson et al.

(10) **Patent No.:** US D741,332 S
(45) **Date of Patent:** ** Oct. 20, 2015

(54) **DATA READER FOR CHECKOUT STATION**

(71) Applicant: **Datalogic ADC, Inc.**, Eugene, OR (US)

(72) Inventors: **Ryan B. Thompson**, Eugene, OR (US);
Jeffrey J. Hoskinson, Eugene, OR (US);
Michael P. Svetal, Eugene, OR (US);
Brianne E. Howard, Eugene, OR (US);
David J. Newman, Eugene, OR (US)

(73) Assignee: **DATALOGIC ADC, INC.**, Eugene, OR (US)

(**) Term: **14 Years**

(21) Appl. No.: **29/523,578**

(22) Filed: **Apr. 10, 2015**

Related U.S. Application Data

(62) Division of application No. 29/493,882, filed on Jun. 13, 2014, now Pat. No. Des. 728,574, which is a division of application No. 29/424,249, filed on Jun. 8, 2012, now Pat. No. Des. 708,183.

CLAIM

We claim the ornamental design for a data reader for checkout station, as shown and described.

DESCRIPTION

FIG. 1 is a front, top, left isometric view of a data reader for checkout station showing the new design;

FIG. 2 is a front, top, left isometric view thereof with the top down reader removed;

FIG. 3 is a right side elevation view thereof;

FIG. 4 is a left side elevation view thereof;

FIG. 5 is a top plan view thereof;

FIG. 6 is a front side elevation view thereof; and,

FIG. 7 is a rear side elevation view thereof.

Broken lines and unshaded portions contained within broken lines are not claimed.

1 Claim, 5 Drawing Sheets
